UNITED STATES PATENT OFFICE.

JAMES H. THOMPSON, OF TRENTON, NEW JERSEY, ASSIGNOR TO HUSSONG DYEING MACHINE COMPANY, OF GROVEVILLE, NEW JERSEY, A CORPORATION OF NEW JERSEY.

YARN RACK.

Application filed June 26, 1928. Serial No. 288,314.

One object of my invention is to make a yarn rack in which the side members and upper and lower cross-bars are made in a single structure, and which structure can be suspended from the ordinary stick-carrying frame of a dyeing machine.

A further object of the invention is to so design the yarn rack that the yarn will be free from contact with all parts of the die 10 vat, with the exception of the yarn rack.

In the accompanying drawings:

Fig. 1 is a perspective view of my improved yarn rack;

Fig. 2 is an enlarged sectional view of one 15 side of the rack, showing details of construction, and also showing the means by which the removable legs are attached to the rack;

Figs. 3 and 4 are perspective views illustrating details of the construction of the 20 fastenings for the legs;

Fig. 5 is a perspective view of the detached head of one of the legs of the rack which are adapted to the recesses in the stick-carrying frame;

Fig. 6 is a view showing the rack in the stick-carrying frame, a vat being shown by dotted lines; and

Fig. 7 is a view illustrating a modification of the means for fastening the detachable 30 legs to the body of the rack.

Referring to the drawing, 1—1 are the side members of the rack, connected together by an upper cross-bar 2 and a lower cross-bar 3. This frame is preferably made of 35 Monel or other suitable metal which will not affect the yarn and which will be smooth, as the invention is intended for use in dyeing silks or rayons.

At the upper end of each side member is 40 a head 4 having an extension 5 (Fig. 5) which projects into the end of the tubular side member and is secured thereto by a pin or other fastening.

One side member of the frame extends the 45 full depth, while the other side member of the frame terminates at "x", (Fig. 1) and has an extension 6 in the form of a tubular leg as shown in Fig. 2. The upper end of this extension abuts against the lower end 50 of the side member 1 as at "x", and secured within the extension in the present instance is a tubular connecting member 7 which extends into the lower end of the side member 1 of the frame.

The upper end of the connecting member 55 7 has a bayonet slot 8 which engages a cross-bar 9 extending across the member 1 of the frame, so that when it is desired to attach the leg to the frame, all that is necessary is to push the leg to the point where it comes 60 in contact with the end of the side member of the frame, and by turning it slightly it will engage the cross-bar 9, holding the leg rigidly in position. On the lower end of each leg is a foot 10 which is secured to the 65 leg by a pin as shown.

When it is desired to place the yarn on the frame, the leg extension 6 is detached from the frame. This allows the skeins of yarn 70 to be passed over the head of the side member and onto the cross-bars of the frame. When all of the yarn is in place, then the leg 6 is coupled to the frame, thus insuring the 75 yarn being held to the frame during the dyeing process, and by again detaching the leg 6, the dyed yarn can be readily removed from the frame.

The heads of the frame are narrow so as to fit into the ordinary stick recesses in the stick-carrying frame 11, the side members 80 12 of which are recessed, the recesses being spaced apart so that the yarn on one frame will not touch that on an adjoining frame.

The side members of the frame hold the 85 yarn away from the sides of the vat, and the cross-bars of the frame are located so that the yarn as it is raised off of the top cross-bar will not be entangled with the side members of the carrying-frame. Furthermore, the heads fit the openings in the frame, so that it will be impossible for any 90 of the material being dyed to come in contact with the vat or carrying-frame, or enter the stick recesses when the die liquor is in 95 circulation.

In Fig. 7 I have illustrated a modification, in which the leg 6^a has a threaded extension 7^a adapted to the threaded end of the side member 1^a.

I claim:

1. A yarn rack for dyeing machines, having side members and connecting upper and lower cross-bars; and detachable legs forming a continuation of the side members below the lower cross-bar.

2. A yarn rack for dyeing machines, having tubular side members and tubular upper

and lower cross-bars; detachable tubular legs forming a continuation of the side members below the lower cross-bar, said legs having portions arranged to extend within the tubular side members, said portions having bayonet slots; and a cross-bar in each side member adapted to be engaged by the said leg extensions.

3. A yarn rack for dyeing machines, having side members and upper and lower cross-

bars, the side members extending above the upper cross-bar and having laterally extending flared heads, said heads being shaped to extend into recesses in the stick-carrying frame of the dyeing machine, the rack having a leg at one side which can be detached when it is desired to place yarn on the rack or remove yarn therefrom.

JAMES H. THOMPSON.
